US0D1107871S

(12) **United States Design Patent** (10) **Patent No.:** **US D1,107,871 S**
(45) **Date of Patent:** **** Dec. 30, 2025**

(54) **URINAL SCREEN**

(71) Applicant: **Fresh Products, Inc.**, Perrysburg, OH (US)

(72) Inventors: **Douglas S. Brown**, Toledo, OH (US); **Jeffrey A. Smith**, Toledo, OH (US)

(73) Assignee: **Fresh Products, Inc.**, Perrysburg, OH (US)

(**) Term: **15 Years**

(21) Appl. No.: **29/865,444**

(22) Filed: **Jul. 26, 2022**

Related U.S. Application Data

(63) Continuation of application No. 29/701,433, filed on Aug. 12, 2019, now Pat. No. Des. 960,329, which is (Continued)

(57) **CLAIM**

The ornamental design for a urinal screen as shown and described.

DESCRIPTION

FIG. 1 is a front, left, and top side perspective view of a first embodiment of a urinal screen embodying our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front side elevational view thereof;

FIG. 7 is a back side elevational view thereof;

FIG. 8 is a front, left, and top side perspective view of a second embodiment of a urinal screen embodying our new design;

FIG. 9 is a top plan view thereof;

FIG. 10 is a bottom plan view thereof;

FIG. 11 is a right side elevational view thereof;

FIG. 12 is a left side elevational view thereof;

FIG. 13 is a front side elevational view thereof; and,

FIG. 14 is a back side elevational view thereof.

Broken lines are used to illustrate features of the urinal screen which form no part of the claimed design.

1 Claim, 10 Drawing Sheets

Related U.S. Application Data

a continuation of application No. 29/592,847, filed on Feb. 2, 2017, now Pat. No. Des. 857,181, which is a continuation of application No. 29/508,397, filed on Nov. 5, 2014, now Pat. No. Des. 778,411.
